UNITED STATES PATENT OFFICE.

JOSEPH T. HOMAN, OF CINCINNATI, OHIO.

DESIGN FOR A COMMUNION-PLATE.

SPECIFICATION forming part of Design No. 26,925, dated April 20, 1897.

Application filed March 12, 1897. Serial No. 627,254. Term of patent 14 years.

To all whom it may concern:

Be it known that I, JOSEPH T. HOMAN, a citizen of the United States, residing at Cincinnati, in the county of Hamilton and State of Ohio, have invented and produced a new and original Design for a Communion or Sacramental Plate; and I do hereby declare the following to be a full, clear, and exact description of the same, reference being had to the accompanying drawings, which form a part of this specification.

My invention comprises a design for a communion or sacramental plate to be used by the Catholic clergy in visiting the sick, the special features of said design being shown in the annexed drawings, wherein—

Figure 1 is a plan of said plate, and Fig. 2 is a vertical section of the same.

The plate has a dished center A, surrounded by a rim B, the extreme outer edge of which is usually milled, as at C. Furthermore, this rim is ornamented with wreaths of oak leaves D and laurel leaves E, united together by a ribbon or bow F, and diametrically opposite said ribbon is a cross G. In the dished center appear three initials "I. H. S."

I claim as my invention—

The design for a communion or sacramental plate, as herein shown and described.

In testimony whereof I affix my signature in presence of two witnesses.

JOSEPH T. HOMAN.

Witnesses:

JAMES H. LAYMAN,
JOHN C. ROGERS.
